WRENCH HAND TOOL

Robert A. Louks, Gilman, Iowa 50106

Filed May 17, 1973, Ser. No. 361,222

Term of patent 14 years

Int. Cl. D8—05

U.S. Cl. D8—22

FIG. 1 is a perspective view of a wrench hand tool in accordance with my new design;

FIG. 2 is a top plan view thereof;

FIG. 3 is a side elevational view thereof, the view of the wrench hand tool from the other side being a mirror image thereof;

FIG. 4 is an end elevational view taken from the left end of FIG. 3;

FIG. 5 is an end elevational view taken from the right end of FIG. 3; and

FIG. 6 is a bottom view of my new design.

I claim:

The ornamental design for a wrench hand tool, substantially as shown and described.
